(57) **CLAIM**

The ornamental design for a light therapy device, as shown.

DESCRIPTION

FIG. 1 is a right perspective view of a light therapy device.

FIG. 2 is a top view thereof;

FIG. 3 is a bottom view thereof;

FIG. 4 is a rear view thereof;

FIG. 5 is a front view thereof;

FIG. 6 is a left side view thereof; and,

FIG. 7 is a right side view thereof.

The broken lines in FIG. 3 depict portions of the light therapy device that form no part of the claimed design; the broken lines form no part of the claimed design.

1 Claim, 5 Drawing Sheets(56)
